UNITED STATES PATENT OFFICE.

ADOLPH SCHWARZ, OF NEW YORK, N. Y.

IMPROVEMENT IN NECK AND FACE PROTECTORS.

Specification forming part of Letters Patent No. 157,640, dated December 8, 1874; application filed October 15, 1874.

To all whom it may concern:

Be it known that I, ADOLPH SCHWARZ, of the city, county, and State of New York, have invented a certain new and Improved Neck and Face Protector, of which the following is a specification:

This invention is illustrated in the accompanying drawing, in which—

Similar letters indicate corresponding parts. This invention consists in a neck and face protector cut out to fit the front part of the head and the neck of a person, and provided with an opening for the face and with suitable fastening devices, in such a manner that when the same is put on and fastened in the rear of the head it protects the forehead, the ears, the chin, the neck, and the shoulders against cold, leaving the eyes, the nose, and the mouth free and unobstructed, and thereby an article of wearing apparel is obtained which is very convenient for use and neat in its appearance.

In the drawing, the letter A designates my new article of wearing apparel, which is made of two pieces of cloth, silk, or any other suitable material, which are united by seams a b. Each of said pieces is cut out with a semicircular or semi-oval recess, so that when the two pieces are united an oval opening, c, is formed, as shown in the drawing. The bottom edges of the two pieces are cut out, so that they fit the neck and the shoulders, while the upper part of the finished article fits the forehead. On the back of the article A is secured an elastic strap, d, which, when the article is to be worn, is passed over the back of the head, while on the lower parts of said article are secured one or more hooks and eyes, e, or other suitable fastening devices, which serve to secure the article on the back of the neck, so that when my protector is fastened in the proper position it incloses the neck, the forehead, and a portion of the back part of the head, while its lower edges extend down over the shoulders, and over the upper portions of the breast and of the back.

The convenience of my protector, particularly for ladies and children, will be fully appreciated by all persons who give it a trial, and it will be readily understood that the same can be ornamented with fur, or in any other desirable manner, according to the taste of the public.

In the example shown in the drawing the face of the person wearing my protector is left entirely free; but, if desired, the opening c can be closed and the protector provided simply with small holes for the eyes, the nose, and the mouth.

What I claim as new, and desire to secure by Letters Patent, is—

As a new article of manufacture, a neck and face protector made to fit the forehead and the neck, and provided with an opening for the face, and with suitable fastenings to retain it in position, all constructed substantially as shown and described.

In testimony that I claim the foregoing I have hereunto set my hand this 13th day of October, 1874.

ADOLPH SCHWARZ.
